(57) **CLAIM**

The ornamental design for a vial as shown and described.

DESCRIPTION

FIG. 1 is a front perspective view of a vial showing our new design;

FIG. 2 is an opposite side front perspective view thereof;

FIG. 3 is a rear perspective view thereof;

FIG. 4 is an opposite side rear perspective view thereof;

FIG. 5 is a front view thereof;

FIG. 6 is a rear view thereof;

FIG. 7 is a front perspective view of an alternative embodiment of a vial showing our new design;

FIG. 8 is an opposite side front perspective view thereof;

FIG. 9 is a rear perspective view thereof;

FIG. 10 is an opposite side rear perspective view thereof;

FIG. 11 is a front view thereof;

FIG. 12 is a rear view thereof;

FIG. 13 is a front perspective view of an alternative embodiment of a vial showing our new design;

FIG. 14 is an opposite side front perspective view thereof;

FIG. 15 is a rear perspective view thereof;

FIG. 16 is an opposite side rear perspective view thereof;

FIG. 17 is a front view thereof;

FIG. 18 is a rear view thereof;

FIG. 19 is a front perspective view of an alternative embodiment of a vial showing our new design;

FIG. 20 is an opposite side front perspective view thereof;

FIG. 21 is a rear perspective view thereof;

FIG. 22 is an opposite side rear perspective view thereof;

FIG. 23 is a front view thereof;

FIG. 24 is a rear view thereof;

FIG. 25 is a front perspective view of an alternative embodiment of a vial showing our new design;

FIG. 26 is an opposite side front perspective view thereof;

FIG. 27 is a rear perspective view thereof;

FIG. 28 is an opposite side rear perspective view thereof;

FIG. 29 is a front view thereof;

FIG. 30 is a rear view thereof;

FIG. 31 is a front perspective view of an alternative embodiment of a vial showing our new design;

(Continued)

FIG. 32 is an opposite side front perspective view thereof;
 FIG. 33 is a rear perspective view thereof;
 FIG. 34 is an opposite side rear perspective view thereof;
 FIG. 35 is a front view thereof;
 FIG. 36 is a rear view thereof;
 FIG. 37 is a front perspective view of an alternative embodiment of a vial showing our new design;
 FIG. 38 is an opposite side front perspective view thereof;
 FIG. 39 is a rear perspective view thereof;
 FIG. 40 is an opposite side rear perspective view thereof;
 FIG. 41 is a front view thereof;
 FIG. 42 is a rear view thereof;
 FIG. 43 is a front perspective view of an alternative embodiment of a vial showing our new design;
 FIG. 44 is an opposite side front perspective view thereof;
 FIG. 45 is a rear perspective view thereof;
 FIG. 46 is an opposite side rear perspective view thereof;
 FIG. 47 is a front view thereof; and,
 FIG. 48 is a rear view thereof.
